UNITED STATES PATENT OFFICE.

JAMES PILLING RENEKER, OF LOGANSPORT, INDIANA

SELF-CLEARING SEGMENT FOR LATHES.

964,316.

Specification of Letters Patent. Patented July 12, 1910.

Application filed July 13, 1909. Serial No. 507,359.

To all whom it may concern:

Be it known that I, JAMES PILLING RENEKER, a citizen of the United States, and a resident of Logansport, in the county of Cass and State of Indiana, have invented a new and Improved Self-Clearing Segment for Lathes, of which the following is a full, clear, and exact description.

My invention relates to lathes for heavy work, and more particularly to center driven car wheel lathes of the Pond type and in which a car-axle is temporarily secured within the axial center of a worm wheel for the purpose of supplying power to the axle in order to cause the rotation of the car wheels and axle relatively to the cutting tool.

More specifically stated, my invention comprehends a worm wheel provided centrally with an aperture having generally the form of a slot for receiving the car axle, and further provided with a sector normally closing the slot, but capable of being moved out of the same in order to permit the ingress and egress of the axle.

My invention further relates to means controllable by the automatic movements of the car axle when moved into and out of the slotted worm wheel for operating the sector.

My invention still further relates to various safety appliances used in connection with the parts just mentioned for the purpose of providing against accident to the machinery or to bystanders.

Reference is to be had to the accompanying drawings forming a part of this specification, in which similar characters of reference indicate corresponding parts in all the figures.

Figure 1 is a front elevation of the lathe showing my improved worm wheel and sector for turning the car axle; Fig. 2 is a rear elevation of the sector and parts immediately associated with it, this view showing the buffer and latch mechanism for locking and unlocking the sector relatively to the worm wheel; Fig. 3 is a detail showing partly in section and partly in elevation the movable sector, and also showing the buffer and latch mechanism carried by it for securing it temporarily in position relatively to the worm wheel; Fig. 4 is a fragmentary view partly in section and partly in elevation, showing the sector as occupying its normal position upon the worm wheel, and also showing the various movable parts as

they appear when the car axle is about to be passed out of the slot of the worm wheel; Fig. 5 is a fragmentary front elevation showing the sector mounted upon the worm wheel and occupying its normal position 61 relatively to the same; and Fig. 6 is a view partly in section and partly in side elevation, showing the various movable parts as they appear when the axle is about to be passed into the slotted worm wheel. 65

A housing 6 is provided with an extension 7 and is disposed intermediate a pair of supporting bases 8. Resting upon the latter are slides 9 and upon opposite sides of these slides are revoluble supporting disks 70 10. Mounted upon this revoluble supporting disk are movable blocks 11 provided with means for connecting them directly to car wheels 12.

At 13 is shown a car axle supporting the 75 car wheels 12. The disks 10 are provided with slots 10^a which are adapted to receive the axle 13.

At 14 are centering devices controllable by hand wheels 15 and provided with center 80 bits 16, the latter being adapted to engage directly the ends of the axle 13.

At 17 are hand levers which co-act with the hand wheels 15 in adjusting the center butts 16. 85

At 18 is a worm wheel which is disposed within the housing 6 and is provided with a rim 19 and teeth 20. The worm wheel is further provided with a large slot 21 extending radially inward from the outer circumference of the wheel to a point a little beyond the center thereof, as will be understood from Fig. 4. A sector 22 having a curvature corresponding to that of the rim 19 is provided with teeth 23 of the same 95 size as the teeth 20 and spaced similarly thereto. Mounted upon opposite sides of the sector 22 are arms 24, 25, integral with the sector, and extending through these arms are screw bolts 26 by aid whereof the sector is suspended and adapted to swing, as may be seen by contrasting Figs. 4 and 6. The sector 22 is provided with two openings 27, 28 and within the latter are two levers 29, 30 mounted pivotally in position by aid of 100 pivot pins 31, 32. These pivot pins are provided with slotted heads 33, 34, by aid whereof they are removable at will. A buffer plate 35 is provided with two cylindrical holes 36 and extending into the latter are 110

two spiral springs 37. These springs engage two rocking plates 38 which are mounted in apertures 39 upon the sector. The sector (see Fig. 2) is provided at its upper end with an edge 40 which is inclined relatively to the general length of the sector, and in this respect is therefore parallel with the general position of the sector teeth 23. In the middle of the edge 40 is a notch 41. The sector at its bottom is provided with another inclined edge 42, and disposed centrally in relation to the latter is a lug 43 projecting downwardly. The sector is moreover provided with shoulders 44, 45, and adjacent to the support 45 is another lug 46 which extends into a slot 47 in the rim of the worm wheel, as will be understood from Fig. 4. Adjacent to the slot 47 are shoulders 46 against which the shoulders 45 may lodge as will be understood from Fig. 4. Disposed upon opposite sides of the slot 41 are lugs 48 which are adapted to lodge against shoulders 49 carried by the rim of the worm wheel. At 50, 51 upon the levers 29, 30 (carried by the sector 22) are latch hooks which are adapted to engage with other latch hooks 52, 53 carried by the rim. The buffer plate 35 is provided centrally with an aperture 54, and fitting into this aperture is a ball 55. By this arrangement the lever 29 can have a rocking movement relatively to the lever 30 when a pressure is applied to the buffer plate 35. The buffer plate 35 is provided with a bevel surface 56 which becomes approximately parallel with the inner surface of the sector 22 whenever the buffer plate is pressed toward the latter. A toggle arm 57 is mounted rigidly upon the sector 22 and is provided with a lug 58, as will be understood from Fig. 4. The toggle arm is also provided with an upwardly projecting portion 59. At 60 is a guide rod which is connected with the portion 59 of the toggle arm by aid of a pin 61. A guide cylinder 62 encircles the guide rod 60 and is mounted upon a pivot pin 63 carried by the worm wheel. Encircling the guide cylinder 62 is a spiral spring 64 and engaging the latter is a collar 65 mounted upon and adjustable relatively to the guide rod 60 for the purpose of controlling the tension of the spring 64. The toggle arm 57 taken in connection with the guide rod 60 and parts immediately associated with the latter forms a toggle joint so arranged as to have two normal positions, one corresponding to the sector 22 as closed (see Fig. 4) and the other corresponding to this sector as open, as indicated in Fig. 6. That is to say, when the sector 22 is closed as indicated in Fig. 4, the spring pressure against the upper end of the toggle arm 57 tends to keep the sector closed tightly; whereas, if the toggle arm 57 be swung downwardly so that the spring pressure is directed as indicated in Fig. 6,

the sector is by this spring pressure held wide open. It seems, therefore, that if an imaginary line be struck through the pivots 63 and 26 when the pivot 61 is at the upper side of this line, the pressure of the spring 64 tends to keep the sector 22 closed; whereas, if the pivot 61 be below the line in question, the tendency of the spring 64 is to keep the sector 22 open. It follows, therefore, that the position of the sector 22, whether open or closed, is controllable by movements of the axle 13 for the reason that this axle, in passing into and out of the slot 21, as indicated in Fig. 6, is adapted to engage the lug 58 and thereby shift the toggle mechanism just described, so as to move the pivot pin 61 above or below the imaginary line between the pivots 63 and 26. The various lugs, shoulders, slots and the like, at the top and bottom of the sector 22, are mainly for the purpose of holding the sector rigidly in position relatively to the worm wheel, so as to prevent the accidental displacement of the sector when the mechanism is in action.

It will be noted that the sector 22 when in the position indicated in Fig. 4, is very securely locked and is necessarily very rigid relatively to the worm wheel. The latch hooks 50, 51 are now in engagement with the latch hooks 52, 53, so that the sector 22 forms virtually a part of the rim of the worm wheel. In order to make the engagement of the sector more secure, the various lugs and shoulders at the top and bottom of this sector grip tightly against the mating lugs and shoulders of the worm wheel, the net result being that the sector 22 can move neither out nor in, up nor down, nor can it move sidewise.

The operation of my device is as follows: Suppose that it be desired to turn in the lathe a pair of car wheels mounted in the usual manner upon an axle as indicated in Fig. 1. The sector 22 is now open, having been left so since the last turning operation upon the lathe. The lathe is so turned as to bring the axle 13 and the slots 10 all into horizontal position. The axle 13 is now passed into the slot 21, as indicated by the arrow in Fig. 6. The axle engages the lug 58 and turns not only the toggle arm 57, but the sector 22, upon the pivot 26 as a center. In doing this the spring 64 is compressed a little until the pivot 61 passes upwardly across the imaginary line joining the pivot 63 with the pivot 26, and after this line is passed, the pressure of the spring 64 causes the pivot 61 to rise and the sector 22 to close. The closing of the sector causes the latch hooks 50, 51 to strike against the latch hooks 52, 53, and thus causes the arms 29 and 30 to swing slightly upon the pivot pins 33, 34. The engagement between the latch hooks being complete, the pressure of the spring 37 by forcing the buffer plate 35 inward

50,510

toward the center of the worm wheel, causes the latch hooks 50, 51 to bind tightly against the inner surface of the latch hooks 52, 53, and thus prevent the accidental disengagement of any of these hooks. The axle being now passed along the slot 21 to the geometrical center of the worm wheel, is locked relatively to the same in the usual manner by aid of temporary chocks employed for the purpose. Power being now communicated to the worm is in turn transferred to the car axle and the wheels are thereby turned. The turning operation being completed and it being desired to remove the axle carrying the wheel, the axle is moved horizontally as indicated in Fig. 4. Striking against the buffer plate, it compresses the spring 37 and bends the arms 29, 30 slightly outward—that is, away from the center of the worm wheel. In doing this, the latch hooks are disengaged and the pressure of the moving axle now causes the sector 52 to swing outwardly, the pivot 61 is thus lowered until it passes below the imaginary line joining the pivots 26, 63, and after this point is passed as above described, the pressure of the spring 64 causes the sector 22 to swing bodily outward, the shaft being thus effectively cleared of its connection with the worm wheel. Suppose, now, that owing to any cause, the power should be accidentally applied to the worm wheel, so as to start the same prematurely into action while the sector 22 is swung outwardly. In this event the teeth 23 (see Fig. 4) strike against the projection 7 of the housing which is immediately over the sector when the latter occupies its normal position. Guided by the projection 7 the sector 22 is forced back nearly into its normal position, and when this occurs the pressure of the spring 64 upon the toggle arm 57 causes the sector to snap into its proper position, and causes the latch hooks 50, 51 to grip relatively to the latch hooks 52, 53. Owing to the gripping action of these latch hooks they may be considered as dogs for holding the sector in a predetermined position.

Having thus described my invention, I claim as new and desire to secure by Letters Patent:

1. A self-clearing segment for lathes, comprising a wheel provided with an opening for receiving an object to be turned, a sector for closing said opening, and means controllable by the relative movement of said object to be turned as said object is passed into and out of its position in said wheel for the purpose of swinging said sector into and out of said opening.

2. The combination of a wheel provided with a slot, a sector movable relatively to said wheel and adapted to close one end of said slot, latch mechanism for locking said sector in position relatively to said wheel,

and means controllable by movements of an object to be turned, as said object is passed out of said slot from its turning position therein, for actuating said latch mechanism in order to release said sector from said wheel.

3. The combination of a wheel provided with an opening for receiving an object to be turned, a sector for closing said opening, a stationary obstruction disposed adjacent to said wheel for forcing said sector toward said opening when said wheel is turned, and means for turning said wheel.

4. The combination of a wheel provided with an opening for receiving an object to be turned, a sector mounted upon said wheel and adapted to swing so as to close a portion of said opening, an obstruction disposed adjacent to said wheel and adapted to be engaged by said sector as said wheel is rotated, so as to move said sector toward said opening, and mechanism connected with said sector and controllable in part by the rotation of said wheel for moving said sector directly into said opening.

5. A device of the character described, comprising a wheel provided with an opening, a sector carried by said wheel and movable relatively to the same, and spring mechanism connected with said wheel and with said sector and controllable by movements of a car axle within said opening for moving said sector directly into said opening.

6. A device of the character described, comprising a revoluble member provided with an opening, a sector movable relatively to said member for temporarily closing said opening, means for preventing said sector from moving laterally in relation to said revoluble member, and mechanism for holding said sector rigidly in a predetermined position relatively to said revoluble member, said mechanism being controlled by the movement of the object to be turned as said object is moved into and out of position in said slot.

7. The combination of a revoluble member provided with an opening for receiving an object to be turned, and further provided with a slot, a sector mounted upon said member and movable relatively thereto, said sector being provided with a portion for entering said slot in order to prevent undesirable motion of said sector relatively to said revoluble member, and mechanism controllable by movements of said object to be turned, as said object is moved into and out of position in said slot, for causing said sector to move bodily in relation to said revoluble member.

8. The combination of a worm wheel provided with a slot, a sector for closing one end of said wheel, toggle mechanism connected with said worm wheel and with said sector for actuating said sector relatively to said

worm wheel, latch mechanism connected with said sector for locking the same rigidly in position relatively to said worm wheel, said latch mechanism being provided with movable members disposed partially in the path of travel of said member to be turned.

In testimony whereof I have signed my

name to this specification in the presence of two subscribing witnesses.

JAMES PILLING RENEKER.
